DEVICE FOR INDICATING TEMPERATURE CONDITIONS

Filed Aug. 8, 1928

Inventor
Albert W. Franklin.

By his Attorneys Dauby & Dauby

UNITED STATES PATENT OFFICE.

ALBERT W. FRANKLIN, OF NEW YORK, N. Y.

DEVICE FOR INDICATING TEMPERATURE CONDITIONS.

Application filed August 8, 1928. Serial No. 298,223.

This invention relates in general to a device for indicating temperature conditions which is particularly adaptable for use on automobile radiators.

5 One of the objects of this invention is to provide a device for indicating temperature conditions of the above nature which is exceedingly simple in construction and which is rigidly constructed for dependable operation.

A still further object of this invention is to provide a device for indicating temperature conditions in automobile radiators which is entirely embodied within the radiator cap without projecting above or below the limiting planes which define the top and bottom of the radiator cap.

20 A still further object of this invention is to provide a device of this nature which has an indicator operated by a bi-metal element.

A still further object of this invention contemplates a device of this nature which being exceedingly simple in construction, is adapted to ready manufacture in large quantities at a very low cost.

These and other objects as will appear from the following disclosure are sought by means of this invention.

This invention resides substantially in the combination, construction, arrangement and relative location of parts all as will appear more fully hereinafter.

Referring to the drawing,

Figure 1 is a top plan view of the device.

35 Fig. 2 is an edge elevational view of the structure of Fig. 1.

Fig. 3 is a bottom plan view of the device with the enclosing plate partially broken away to show the interior thereof.

40 Fig. 4 is a vertical cross sectional view taken on the line 4—4 of Fig. 2.

Devices employed heretofore in this art for indicating temperature conditions in automobile radiators have been termed "motometers". In devices of this nature now available, it has been the practice to support the structure on the radiator cap with portions thereof projecting above and below the upper and lower surfaces of the cap.

50 The portion projecting below the cap extended into the radiator so as to be subjected to the temperature conditions therein, while the portion extending above the cap gave a visible indication of these temperature conditions. Such a device is not only installed from a decorative view point but is

also in the nature of its construction subject to injury and breakage. At the same time, such devices are relatively expensive to make.

The device of this invention is of such a simple nature as to make it cheap to manufacture. It is also by reason of its construction neat in appearance and tends to improve the appearance of cars to which it is applied. The most important feature of the invention is the fact that all the operative elements thereof are enclosed within the radiator cap so that there are no projections above and below the cap. These parts are sealed within the cap so that no moisture may get at them and as a result there is no tendency for the device to get out of order, because of corrosion and the like. In the device the essential parts consist of an indicator controlled by a bi-metal element which has the two functions of holding the indicator in non-indicating position under normal temperature conditions and moving the indicator into indicating position upon the development of abnormal temperature conditions.

Reference is now made to the drawings in which the device is shown comprising a relatively flat cup shape radiator cap 1, provided with an arcuate opening 2. This opening is covered with any suitable transparent material 3 through which the indicator device may be used. A portion of the cap 1 is internally threaded as at 4 so that it may be secured to the radiator in the usual and well known manner.

45 A plate 5 is used to provide a closed chamber 6 in cooperation with the cup shape portion of the cap and is held in place by means of screws. The operative parts of the device are held within the chamber thus formed which chamber is completely closed by reason of the air tight connection between the cap and the plate. Secured to the plate 5 so as to be within chamber 6 is a short post 7 on which is mounted a bi-metal element 8. As is well known, the bi-metal element merely consists of two metals of different temperature coefficients rigidly secured together so that they distort when heated due to the unequal expansion of the different metals. The bi-metal element 8 is provided with three U-shape portions 15, 16 and 17 for the purpose of magnifying the effect of the distortion of the bi-metal element, and to produce a spring action as will be described later pivotally mounted on the plate 10

which is secured to plate 5, is an arm 11 having an arcuate portion extending at an angle thereto as shown at 12. These parts are arranged so that as arm 11 swings in a 5 counter clockwise direction, Fig. 3, the indicator portion 12 moves in front of window 2 an amount depending upon the temperature conditions being registered. The surface of the indicator 12 which appears 10 through the opening 2 may be painted in some easily, visible color such as red. The vertical portion of arm 11 is provided with a small slot into which the free end of the bi-metal element 8 extends. The fixed pins 15 13 and 14 are provided to limit the movement of the arm 11. When this arm is against pin 14 the indicator 12 is visible through the opening and indicates normal or subnormal temperature conditions. When 20 the arm 11 is against pin 13 the indicator 12 is wholly exposed through the opening and indicates abnormal or dangerous temperature conditions.

It is of course apparent that the device 25 may be calibrated so that dangerous conditions are indicated before the indicator 12 is wholly exposed as for instance when it is only one-half exposed. Besides having the function of controlling the movement of arm 30 11 and indicator 12 under varying temperature conditions, the bi-metal element 11 also operates to hold the arm 11 against stop pin 14 under low temperature conditions or non-indicating position.

35 From the foregoing disclosure it will be apparent that this device is exceedingly novel and embodies valuable and practicable principles of operation and construction.

I am well aware that many changes in 40 the details of construction and relative arrangement of parts will readily occur to those skilled in this art and I do not therefore desire to be particularly limited to the features of construction as set forth for purposes of illustration but rather to the principles of construction and operation as set forth in the appended claims.

45 I wish to point out that although this device has been disclosed as applied to an automobile radiator, it is of course apparent that it is applicable to any mechanism subjected to temperature changes in which it is desired to have an indication thereof.

What I seek to secure by United States Letters Patent is:

55 1. In a radiator cap of the type described the combination comprising a cup shaped member, a detachable wall therefor to provide a closed chamber, said cup shape member having an opening therein which is closed by a transparent element, an indicator within said chamber and means within the chamber and connected to the indi-

cator element for moving it under changes in temperature so as to render it more or less visible through said opening dependent upon temperature conditions. 65

2. In a radiator cap of the type described, a flat container having an opening therein covered by a transparent element, a movable indicator element within the container, heat influenced means connected to said movable indicator element for rendering it more or less visible through said opening depending upon the temperature conditions to which the heat influenced element is subjected, said indicator element and said heat influenced means lying wholly within said flat container. 70

3. In a radiator cap of the type described, the combination comprising a flat container having an opening therein, said container having means for securing it to a radiator, an indicator arm movably supported within the container and a bi-metal member within the container and operatively connected to said arm to move it into and out of alignment with said opening under varying temperature conditions, to said indicator element and bi-metal member lying wholly 85 within said flat container. 90

4. In a device of the type described, the combination comprising a flat radiator cap having an opening therein closed by a transparent wall, a removable plate for forming a closed chamber with said cap, an arm pivotally supported on said plate within said chamber so as to be adapted for movement into and out of alignment with said opening and a bi-metal element within said cap and operatively connected to said arm for changing its position with respect to said opening depending upon the temperature conditions within the radiator to which the cap is to be applied, said bi-metal element also acting to resiliently hold said arm out of alignment with said opening under ordinary temperature conditions, all of the operating parts lying entirely between the cap and plate. 100 105 110

5. In a device of the type described, the combination with a flat radiator cap having an opening therein and a plate detachably secured within said cap to form a closed chamber, of means within the chamber for giving a visible indication through said opening of the temperature conditions within the radiator to which a cap is to be applied, the vertical extent of the complete device being defined by the top of the radiator cap and the lower edge thereof. 115 120

In testimony whereof I have hereunto set my hand on this 2nd day of August, A. D. 1928.

ALBERT W. FRANKLIN.
